ANTENNA SYSTEM

Raymond S. Yoder and Henry B. Saunders, Chicago, Ill., assignors to Galvin Manufacturing Corporation, Chicago, Ill., a corporation of Illinois

Application January 23, 1940, Serial No. 315,240

12 Claims. (Cl. 250—11)

This invention relates to antenna systems for radio receiving apparatus and in particular to an adjustable loop antenna for radio receiving apparatus for mobile craft.

In antenna systems for automobiles, it is of the utmost importance that the system be not only very efficient in its signal pick-up, but also as inconspicuous as possible so as not to impair the appearance of the car. Ordinary antennae of the horizontal and vertical types have been substantially exclusively used in connection with automotive radio receivers, because their elongated form is adapted to installations which are made relatively quickly, and such form does not interfere greatly with the handling of the car. These antennae, however, seldom add to the appearance of the car and moreover cannot be adjusted relative to the direction of radio and interference waves to vary in this manner the ratio of signal energy to noise so as to improve the radio selectivity and reception.

The conventional auto antenna of straight type is not resonant to any frequency in the usual broadcast band and approaches resonance near the band of interfering frequencies. In some instances of travel, therefore, such as in the proximity of street car lines, signs, power lines and the like, the radio signal picked up by these antennae is rendered indiscernible, since the discernibility of the signal depends not only upon the actual strength of the signal energy, but also upon the ratio of the signal energy to that of the interfering noises. This condition is particularly objectionable in city travel, because of the heavy distribution of power lines.

Although it is well known that a directional receiving antenna serves to vary the ratio of signal energy to noise, so as to improve reception, the directional antennae now commercially available are too bulky and unwieldy for satisfactory use in connection with automotive radio receivers.

It is an object of this invention, therefore, to provide an improved loop antenna for radio apparatus for moving craft of all types.

It is a further object of this invention to provide a loop antenna having a narrow width, so that the antenna may be of such overall design as to be easily and conveniently located on the outside of an automobile body without impairing the appearance of the car, nor introducing undesirable wind resistance.

It is another object of this invention to provide a loop antenna for an automotive radio receiver which is adapted to effect a higher fidelity and

selectivity in the receiver than has heretofore been possible in radio receivers for automobiles using the ordinary type antennae.

It is a still further object of this invention to provide a loop antenna for an auto radio receiver which can be mounted on the inside of the car in a compact assembly, conveniently located and readily accessible. The outside of the car is thus free of any defacement, and the antenna is positively protected from exposure to weather conditions.

A further feature of this invention is the provision of a loop antenna for auto-motive radio receivers, which is remotely located from the receiver but electrically connected with the receiver by a coaxial transmission cable.

Another object of this invention is to provide a loop antenna for auto radio receivers having a configuration that provides for a relatively high pick-up mass.

It is a particular feature of this invention to provide a loop antenna of narrow width and high pick-up mass and a protective housing therefor, which is adapted to minimize the interference effects from wheel and tire static and to substantially reduce the electro-static noise coupling induced by surrounding interference sources.

It is yet another object of this invention to provide a loop antenna for a receiver on a power operated craft which is of rugged construction, of a construction for simple installation, and of low cost, and which is particularly effective in reducing the static noises from the motor of the craft.

Further objects and advantages of the present invention will become apparent from the following description, when taken in connection with the accompanying drawings, in which:

Fig. 1 is a portion of a radio circuit illustrating the connection of the improved loop antenna therein.

Fig. 2 illustrates a manner of mounting the antenna on the outside of the car body, the antenna and housing therefor being shown in section and portions of the mounting being in section and broken away. For the purpose of clarity, the antenna and housing are drawn larger than the proportional size in comparison with the car body and the coaxial transmission cable is shown in its actual size.

Fig. 3 is an enlarged sectional view of the antenna as viewed along the line 3—3 in Fig. 2.

Fig. 4 is a modified form of the invention showing the antenna located inside of the car body adjacent the dashboard.

Fig. 5 is a sectional view of the housing as seen along line 5—5 in Fig. 4.

Fig. 6 is a further modification of the invention with the antenna located inside of the car and mounted in connection with a rear vision mirror.

Fig. 7 is a fragmentary view showing another arrangement of the antenna and rear vision mirror in the modification of Fig. 6.

Fig. 8 illustrates a further embodiment of the invention with the antenna mounted on the outside of the car body.

Fig. 9 is a sectional view taken on the line 9—9 in Fig. 8.

Fig. 10 is a showing in actual size of a loop antenna adapted for use with the mounting structure in Fig. 1; a portion of the antenna housing being broken away to show the construction of the housing and the positioning of the antenna loop therein.

Fig. 11 is a fragmentary sectional view through a wall of the antenna housing as seen along line 11—11 in Fig. 10, showing the electro-static shield, and a plan view of the loop antenna, and

Figs. 12 and 13 are fragmentary sectional views illustrating modified forms of an electro-static shield structure for the antenna housing in Fig. 10.

With reference to the drawings, wherein similar parts are designated by similar numbers throughout the various views, there is shown in Fig. 2, an automobile 10 having a radio receiver 11 disposed adjacent the dashboard 12. The radio receiver is in operative association with a loop antenna 13 which is mounted on the roof of the car and is provided with an electro-static shielded housing 14. The antenna 13 and housing 14 are drawn for clarity to an enlarged scale in comparison to the car, the actual housing in one commercial embodiment being only about seven and one-half inches long and three and one-half inches in diameter at its widest sections, and the antenna having a width of less than three inches.

The antenna 13 is of substantially spiral form with the coil windings thereof arranged in the same plane, as is clearly shown in Fig. 3. To provide for a high proportion of antenna width to antenna depth it is contemplated that the antenna wire of relatively low gauge, the antenna width being indicated by the lines A—A and the antenna depth by the lines B—B. By virtue of this construction the antenna has a relatively large pick-up mass or, in other words, a relatively high signal receiving capacity. Also, an antenna of this configuration is found to possess a very high Q resulting in greater station selectivity as to adjacent channels of frequencies.

The housing 14 is preferably formed of an appropriate phenolic resin or the like, and includes mating halves 16, only one of which is shown in Fig. 2, which are provided over their inside surface with a plurality of conductors 17, which form an electro-static shield therein. Since every conductor provides for a possible formation of eddy currents, the conductors 17 are of small cross section but of a relatively high ratio of width to depth, and are formed of a high conducting material to effect the greatest advantage in the elimination of the eddy currents. The conductors 17 are arranged in each housing half 16 to emanate from a common central zone designated as 18 in a direction toward the edges of such half. The zone 18 is also shielded with a conductor element which is connected with all of the conductors 17 which terminate at the

edges of the housing half 16. It is thus seen that the combined surface area of the conductors 17 is substantially equal to the total inside surface area of the housing 14. It is to be noted that the connecting zone 18 is substantially opposite the central portion of the antenna 13, so that the eddy current effects on the antenna are reduced to a minimum. The conductors 17 are raised from the inside surface of the housing walls and are separated from each other by spaces 19, which are formed between adjacent conductors.

The conductors 17 may be formed by placing a suitable mask over the inside surface of the housing half 16 and then spraying the mask with aluminum or copper, which adheres to the unmasked housing surface, the masked surface portions providing for the spaces 19. A shielded housing of this construction, has been found to effect a very sharp null in the interfering frequencies for a small angular directioning of the antenna so as to maintain a high ratio of signal energy to noise over a broad wave spectrum.

The housing 14 is provided with a base portion which conforms substantially to the curvature of the top of the car 10, a gasket 21 positioned between the housing 14 and the top of the car 10 serving to seal the interior of the housing and hence the antenna from exposure to the weather, and contamination from dirt, grit and the like. The antenna is suitably mounted to the end 22 of a coaxial transmission cable 23, which serves to electrically connect the antenna with the receiver 11, in a manner to be hereinafter fully described. The cable is commercially available and includes substantially cylindrical segments 24, which are adapted to be extendingly arranged in a capped formation. Each segment 24 is formed of a dielectric material and is provided centrally thereof with a conductor 26, which extends therethrough so as to engage the conductors 26 in the adjacent segments. A continuous insulated conductor is thus formed by the mating assembly of the segments 24. The segments 24 are arranged within a shield 27, which in turn is covered with a flexible housing 28. The cable 23 is thus seen to be both stiff and pliant.

The cable 23 is rotatably mounted in a sleeve 29 of conducting characteristics which in turn is supported in the roof of the car 10 in a manner to be in conducting relation therewith. The sleeve 29 is formed with an outwardly flanged end 31 which is located within the housing 14 and adapted to engage the gasket 21 (Fig. 4). The opposite end of the sleeve 29 is formed with threads for engaging a nut 32, tightening of the nut 32 serving to press toward the car top the spring member 33 to hold the sleeve 29 in the car top, in an obvious manner. The nut is formed with an inwardly extending unthreaded annular portion 34, which fits loosely about the cable 23, and serves to position the cable within the sleeve 29. The cable 23, near the antenna end 22 has fastened thereto a collar 36, which is adapted to be supported on a tension washer 37, which in turn is supported on the flanged end 31 of sleeve 29. The collar 36 serves to maintain the antenna properly located within the housing 14, the collar 36 and locking collar 38 cooperating to keep washer 37 under sufficient tension to substantially eliminate any jarring action of the antenna during normal operation of the automobile.

As noted above, it is contemplated that the

sleeve 31 be formed of a material having conducting characteristics. Since the sleeve is in conductive relation with the top of the car 10, an unbalanced antenna, having a ground connection of very low impedance is provided by connecting the low potential side of the antenna 13 to the sleeve 29. Static noises picked up by the antenna 13 are thus readily conducted to the ground, whereby to obtain an appreciable reduction in the static which might otherwise be conducted to the receiving apparatus.

The high potential side of the antenna 13 is connected to the lead-in or conductors 26 in the cable segments 24, for transfer of the signal response to the receiver 11, connection of the lead-in 26 and the receiver being made through a pin connection 40 which includes a pin 41 and a pin receiving socket 42; the pin 41 being connected with the lead-in 26, and the socket 42 being connected to the condenser 43, by means of the conductor 44. The pin 41 is maintained in the socket portion 42 by threading of the nut 46 about the threads formed on the socket portion. The pin connection is thus seen to provide for a simple relatively movable connection between the cable 23 and radio 11 to maintain electrical contact therebetween upon rotation of the cable 23. To facilitate rotation of the cable 23 and hence directioning of the antenna, there is provided a knurled knob 47, which is located so as to be readily manipulated by the driver of the car. It is thus seen that the cable 23 serves to electrically connect the antenna 13 with the radio 11, to orient the antenna from the radio, and to support the antenna for directioning purposes.

With reference to Fig. 1 the antenna 13 is shown in circuit with a portion of a simple radio circuit. The high potential side of the antenna is fed to the grid of a first R. F. amplifier or modulator 48, through conductors or lead-in 26 and a capacitive coupling or fixed isolating condenser 49. The variable condenser 43 is connected across the antenna circuit, and the low potential side of the antenna is grounded to the sleeve 29 through conductor 51. There is thus provided a resonant circuit for the antenna 13, the loop serving as an antenna or inductance coil, and resonance with each frequency being obtained by the tuning of the condenser 43. As noted above, the particular configuration of antenna 13, with the transverse diameter very much greater than the cross-sectional width, as shown in Fig. 2, provides for a greater pick-up mass and hence for a greater effective height than is obtainable with a vertical antenna. This increase in pick-up mass and the resonant characteristics of the antenna circuit provide for an increase in the signal pick-up and hence in the ratio of signal energy to noise.

A modified form of antenna 13 and housing 14 adapted for use with the radio circuit of Fig. 1 and the structure of Fig. 2, is shown in Fig. 10. The antenna 52 is of spider construction and of substantially oval configuration; the spider frame 50 being relatively narrow to provide for a high ratio of antenna width to depth. The housing 14' is composed of similar halves 16' and is of a form similar to that of the housing 14. Each housing half 16' is provided over its inside surface with conductors 17', spaces 19', and a connecting zone (not shown), which are similar to the conductors 17, spaces 19, and zone 18, respectively, hereinabove described in connection with Fig. 2. The outside surface of each half 16' is provided with conductors 53, 75

which are similar to conductors 17, but are staggered relative thereto, to provide a solid shield, projectively, about the antenna 52, as is clearly shown in Fig. 10. Since the conductors 17' and 53 are in a projected overlapped relation it is readily apparent that the projected area of all of the conductors 17' and 53 completely covers the surface area of the housing 14'. The conductors 53 are separated from each other by spaces 54, and are arranged to emanate from a common central zone 56 in a direction toward the edges of the housing half. The zone 56 is shielded with a conductor element which is connected with all of the conductors 53, the connecting zone for the conductors 17' and the zone 56 being arranged substantially opposite each other for electrical connection by a rivet 57 or the like. Since the connecting zones for the conductors 17' and 53 are also substantially opposite the central portion of the antenna 52, it is seen that the effect of the eddy currents on the signal response of the antenna is reduced to a minimum. There is thus provided an antenna 52 of high pick-up mass and a housing therefor, having a shield, which is solid, projectively, about the antenna for all operating positions of the antenna.

Modified forms of shielding structures, which may be used in the housings 14 and 14' are illustrated in Figs. 12 and 13. With reference to Fig. 12 the shield is molded within the housing wall 59 and is formed from a single flat piece of copper or like material, the flat conductors 61 being extruded and angled, as shown, but connected to a common conductor 62. It is to be noted that the angle of the conductors 61 provides for a projected area of the conductors which is substantially equal to the surface area of the housing. In Fig. 13 the shield is comprised of wire rods 64, which are arranged substantially radially in the housing wall, the inner ends of the wires 64 being in common connection at a central zone (not shown) similar to the zones 18 and 56, which were described above; the rods 45 being positioned in close relative proximity to provide a projected area which is substantially equal to the surface area of the housing.

A modified form of the invention is shown in Fig. 4. The loop antenna 66 is composed of two spirally wound coils 67, which are connected in series and arranged within a spherically shaped housing 68. The antenna 66 and housing 68 are located within the body of the car 10 adjacent the windshield (not shown), but independent thereof, whereby to provide for an efficient signal pick-up. The antenna 66 and the housing 68 are both relatively small and may be mounted on or adjacent the dashboard 12 without impairing in any way the vision of the driver of the car. The housing 68 is rotatably mounted in the dashboard 12 by a suitable mounting means designated generally as 69. The housing includes a tubular extension 71 in the flat bottom-portion 72 thereof which is adapted to extend through and be rotated in the mounting blocks 73 and 74, the portion 72 being supported in rotative engagement on block 73. The blocks 73 and 74 are located on opposite sides of the dashboard 12 and are secured together by screws 76. The lead-in wire 71 is positioned substantially centrally of the extension 71, by annular spacers 78 which are formed of a suitable dielectric material; the extension serving as a shield for the lead-in 71. The extension 71 is fastened to the pin of the pin connection 40, the lead-in 71 be-

ing connected by the pin assembly 40 and conductor 44 to the condenser 43, in the manner hereinabove described with reference to Fig. 2. It is to be noted that the extension 71, spacers 78 and lead-in 77 provide for a coaxial transmission cable between the antenna 66 and the receiver 11, the cable being rotatable with the housing 68. The antenna is mounted for rotation with the housing by connection of the high and low sides thereof, to the lead-in 77 and extension 71, respectively, the extension serving to ground the antenna to the frame of the car 10. A directioning of the antenna is thus readily obtained by a suitable turning of the housing 68.

The housing 68 is formed of two mating halves 79, which are secured together as by screws 81. The housing 68 is provided with an electro-static shield of a structure shown in Fig. 5. Each housing half 79 has formed over its inner surface conductors 83, which extend radially from a common zone 84 to the outer edges of such half. The conductors 83 are separated from each other by spaces 86, and are connected at the common zone 84 which, in the housing assembly, is located substantially intermediate the spiral coils 67, so as to reduce to a minimum the effects of eddy currents on the antenna 66. The conductors 83, zone 84 and spaces 86 are formed in a manner similar to the conductors 17, zone 18 and spaces 19, respectively, which were described in connection with Fig. 2.

A further modified form of the invention is shown in Fig. 6 in which an antenna 13 is mounted in a housing 87 which is adapted for assembly with a rear vision mirror 88. The mirror 88 and housing 87 assembly is provided with a ball portion for a ball and socket connection with a bracket 89, mounted adjacent the windshield 70, but independent thereof. The housing 87 is of substantially flat circular form and includes an electro-static shield (not shown) of a form and structure substantially similar to that described and shown in Fig. 5. The antenna 13 is connected with the radio receiver 11 by the coaxial transmission cable 23 which is suitably mounted in the frame of the car 10. The lead-in 26 is connected to the tuning condenser 43 in the receiver circuit by the pin connection 40 and conductor 44 which were hereinabove described. The opposite end of the lead-in or conductor 26 is electrically connected to the high potential side of the antenna 13 through a suitable ball connection 91; the low potential side of the antenna being grounded to the shield 27 through ball connection 92. It is to be noted that the housing 87, antenna 13 and mirror 88 are all movable as a unit, relative to the cable 23; the pin connection 40 serving primarily as an assembly expedient.

With reference to Fig. 7 there is shown a modified arrangement of the antenna system in Fig. 6. The bracket 93 is mounted adjacent the windshield 70, but independent thereof, and is formed with a pair of extending fingers 94. Each finger 94 is provided with a socket portion for a ball and socket connection with a mirror 96 and antenna housing 97, respectively; the housing 97 and antenna 13 being located adjacent the mirror 96, but independent of the windshield 70. The mirror 96 and housing 97 are suitably arranged to provide for maximum adjustability of the mirror 96 and the antenna 13; the housing being disposed so that full vision can be obtained through the rear view mirror. It is thus seen that the mirror 96 and antenna 13 are relatively mov-

able for independent adjustment and that the housing 97 is so located as to permit full vision of the driver in both the mirror 96 and through the windshield 70.

It is to be understood that in the embodiments of the invention disclosed in Figs. 2, 4, 6 and 7, a proper directioning of the loop antenna is obtained by a turning movement of about fifteen degrees, so that a proper directional setting is easily accomplished. In the embodiment of Fig. 6, therefore, the assembly of the antenna 13 with the rear vision mirror 88 does not materially impair the intended utility of the mirror.

Yet another form of the invention is illustrated in Fig. 8. The antenna (not shown) is mounted within the housing 98 so as to be rotatable therewith, the housing being provided with a hollow extension 99 having a mounting portion 101 thereon adapted to engage the end of a tube 102. The tube 102 which is formed of brass or like material, is rotatably mounted in the top of the car 10, the lower end of the tube being provided with a ball joint 103 for reception in a socket portion 104 arranged on the dashboard 12 of the car 10. The antenna lead-in wire 106 from the antenna passes through the extension 99 and tube 102 for electrical engagement with the ball portion 103. As shown in Fig. 9 the lead-in wire 106 is arranged substantially centrally of the tube 102 by annular spacers 107 which are formed of a suitable dielectric material. It is thus seen that a coaxial transmission cable is provided for connecting the antenna with the radio receiver (not shown), the receiver being in electrical connection with the socket portion 104.

It is to be noted that the low potential side of the antenna may be effectively grounded by the tube 102 and car 10 by means of a connecting conductor (not shown) arranged in the extension 99. Directioning of the antenna is obtained by turning of the knob 108, the amount of turning and hence a particular directional setting of the antenna being determined from a suitable indicator 109. It is to be noted that the housing 98 is of a configuration simulating that of a spotlight so that a turning of the housing for directioning of the antenna, does not in any manner detract from the appearance of the car.

It is thus seen that the present invention provides for a shielded loop antenna for radio receivers on mobile craft, which is very small, compact and rugged of design and which provides for a high Q, and a high ratio of signal energy to noise over a broad wave spectrum. The small dimensions of the antenna provide for the location of the antenna either in the inside or on the outside of a car body without in any manner impairing the appearance of the car by reason of its bulk or unsightliness.

Although the present invention has been described and illustrated in connection with automotive radio apparatus, it is to be understood that it is not to be so limited, since its application may be extended to all mobile craft such as boats, trains, airplanes and the like. It is to be understood also that each of the shield structures illustrated in Figs. 2, 5, 10, 12 and 13 may be used in connection with the antenna housings shown in Figs. 2, 4, 6, 7 and 8. The circuit diagram in Fig. 1, although described specifically in connection with the embodiment in Fig. 2, also represents a radio circuit for the antenna systems shown in Figs. 4, 6, 7 and 8.

It is to be understood further that only preferred embodiments of the present invention have

been illustrated and described herein and that further modifications and alterations thereof may be made within the full intended scope of the invention as defined by the appended claims.

We claim:

1. In an antenna system for a mobile craft radio receiving system with said craft having a low impedance ground circuit, an unbalanced loop antenna having the low potential side thereof connected into the low impedance ground circuit of said craft, said antenna being of a width less than three inches and formed of low gauge wire wound in a substantially spiral form and providing a relatively high pick-up mass, a housing for said antenna, said housing being formed of insulating material and having therein an electro-static shield including conductors which are distributed substantially over the complete surface area of said housing, said conductors being connected at a common zone which is located adjacent an antenna portion of low signal pick-up to reduce to a minimum the effect of eddy currents on said antenna, and means for directly rotating said antenna, said antenna and housing serving to effect a sharp null in the field of interference frequencies to maintain a high ratio of signal energy to noise over a broad wave spectrum.

2. In an antenna system for a mobile craft radio receiving apparatus, a loop antenna of substantially spiral configuration with the windings thereof in the same plane and formed of a low gauge wire to obtain a high proportion of antenna width to antenna depth, a housing for said antenna, said housing being formed of insulating material and having therein an electro-static shield including conductors having a projected area which substantially covers the complete surface area of said housing said conductors being connected at a common zone which is disposed substantially opposite the central portion of said antenna to reduce to a minimum the effect of eddy currents on said antenna, and means for directly rotating said antenna, said antenna and electro-static shield serving to effect a sharp null in the interference frequencies, to maintain a high ratio of signal energy to noise over a broad wave spectrum.

3. In antenna apparatus for automotive radio receiving apparatus, a loop antenna including a lead-in wire for electrical connection with said receiving apparatus, said antenna being located outside of said automobile body, a stream-lined housing for said antenna, a tubular support for said housing extending to the radio receiving apparatus and being substantially straight over its entire length, said tubular support being adapted to receive the said lead-in wire therein to provide a coaxial transmission cable between said antenna and radio receiving apparatus, and means for rotatably mounting said tubular support in the automobile body, said tubular support and the car body serving as a ground circuit for the low potential side of said antenna.

4. In antenna apparatus for a mobile craft radio receiver including a loop antenna, an insulating housing for said antenna formed with a pair of mating portions, an electro-static shield in said housing including conductors of relatively small cross-section but having a high ratio of width to depth, distributed over substantially the complete inside surface of each of said housing portions, said conductors being directed from a central zone on the inside surface of each

housing portion to the edges thereof, said zone being provided with a conductor common to all of said first conductors.

5. In an antenna system for automotive radio receiving apparatus, having an antenna mounted on the outside of the car body and a radio receiver mounted within the car body adjacent the dashboard, a coaxial transmission cable substantially straight over its entire length for electrically connecting the antenna with said radio receiver, said antenna being of substantially spiral form with the windings thereof in the same plane, a housing for said antenna formed of mating halves and having an electro-static shield therein including conductors having a projected area substantially equal to the surface area of said housing, the conductors in each housing half being connected together at a common zone, said zones being substantially oppositely disposed adjacent the central portion of said antenna, said antenna being supported on said coaxial cable, and means for rotatably mounting said coaxial cable in said car body.

6. In antenna apparatus for a mobile craft radio receiver, a loop antenna located remotely from said receiver, a coaxial transmission cable for electrically connecting said antenna with said receiver, a housing for said antenna formed with mating halves and having an electro-static shield built therein, each of said housing halves being provided with conductors which substantially cover the inner surface thereof, said conductors being connected at a central common zone and extending radially therefrom to the edges of such housing half, said coaxial cable extending within said housing and having said antenna supported thereon, means for rotatably mounting said coaxial cable in the mobile craft, and a pin connection for rotatably connecting said coaxial cable with said receiver.

7. In antenna apparatus for automotive radio receiving apparatus, a loop antenna having a lead-in line for electrical connection with the receiving apparatus, said antenna being located outside of said automobile body, a stream-lined housing for said antenna having an electro-static shield therein, the projected area of said shield substantially covering the surface area of said housing, a tubular support for said housing extending to the radio receiving apparatus and being substantially straight over its entire length, said tubular support being adapted to receive the said lead-in line therein to provide a coaxial transmission cable between said antenna and radio receiving apparatus, and means for rotatably mounting said tubular support in the automobile body including a ball and socket connection which forms a part of the antenna lead-in line.

8. In antenna apparatus for a mobile craft radio receiver including a loop antenna having a portion of low signal pick-up, an insulating housing for said antenna, an electro-static shield in said housing including spaced conductors having a projected area which covers completely the surface area of said housing, said conductors being in electrical connection with a common portion which is located opposite said antenna portion of low signal pick-up, to reduce to a minimum the effects of eddy currents on said antenna.

9. In antenna apparatus for a mobile craft radio receiver including an antenna, an insulating housing for said antenna, an electro-static shield for said antenna including metallic painted portions on said housing having a projected

area which covers completely the surface area of said housing, said portions being arranged on opposite sides of the housing wall in a projected overlapping relation and being connected together at points adjacent antenna portions of low signal pick-up, to reduce to a minimum the effects of eddy currents on said antenna.

10. In antenna apparatus for a mobile craft radio receiver, a loop antenna of narrow width and of substantially oval configuration, a two part insulated housing for said antenna, an electro-static shield in said housing including conductors formed on opposite sides of said housing wall in a projected overlapping relation, to provide a shield having a projected area which completely covers the surface area of said housing, all of the conductors on each of said housing parts being connected together at a common zone, said zones being substantially oppositely disposed and located adjacent the central portion of said loop.

11. In an antenna system for the radio receiver of a mobile craft, said craft having body means, and said radio receiver being mounted within said body means, a loop antenna having a portion of low signal pick-up, a housing for said antenna supported on said body means, said housing being composed of an insulating material and including an electro-static shield having metallic coated sections, conductor means common to said

metallic coated sections and positioned opposite said antenna portion of low signal pick-up, a coaxial transmission cable of substantially straight form electrically connecting said radio receiver with said antenna, and means supporting said coaxial cable within said body means.

12. In an antenna system for a mobile craft radio receiving system having an input circuit, said craft having a low impedance ground circuit, a loop antenna with a portion of low signal pick-up, said antenna having the low potential side thereof connected with the low impedance ground circuit of said craft and the high potential side thereof connected with said input circuit,
- 15 a housing for said antenna formed of insulating material, and including an electro-static shield having metallic portions arranged substantially over the complete surface area of said housing, said metallic portions being electrically connected together at a portion of said housing which is located opposite said antenna portion of low signal pick-up to reduce to a minimum the effect of eddy currents on said antenna, said antenna and housing serving to effect a sharp null in the field of interference frequencies to maintain a high ratio of signal energy to noise over a broad wave spectrum.
